UNITED STATES PATENT OFFICE.

PHILIPP METTMANN, OF PHILADELPHIA, PENNSYLVANIA

BOX AND CLOSURE THEREOF.

No. 869,924.

Specification of Letters Patent.

Patented Nov. 5, 1907.

Application filed December 21, 1906, Serial No. 7,8,312.

To all whom it may concern:

Be it known that PHILIPP METTMANN, a citizen of the United States, residing at Philadelphia, in the county of Philadelphia and State of Pennsylvania, has 5 invented new and useful Improvements in Boxes and Closures Thereof, of which the following is a specification.

This invention relates to new and useful improvements in boxes and relates more particularly to closures therefor.

It is an object of the invention to provide a novel device of this character wherein the cover of a box is securely held in position and yet in such manner as to be readily removed.

15 It is also an object of the invention to provide a novel device of this kind wherein the cover retaining means may be employed time and again without replacing the means.

It is a custom in securing covers to boxes or other receptacles in such a manner that said securing means must be destroyed before the cover can be removed. This invention obviates this disadvantage.

Furthermore the invention has for an object the provision of a novel device of this character that will be 25 simple in construction, efficient in practice and economical to manufacture.

With the above and other objects in view the invention consists in the novel arrangement and construction of parts and in the details of construction to be herein- 30 after described.

In describing this invention in detail reference will be had to the accompanying drawing wherein like characters of reference denote corresponding parts in the several views and in which

35 Figure 1. is a perspective view of a box illustrating the invention applied thereto, and Fig. 2. is a similar view, the cover being shown detached.

In the drawing, 1 denotes a box or other receptacle and 2 a cover therefor which when in applied position, rests upon the guide or supporting strip 9. This cover 40 may be hinged at one edge of the box or be entirely free thereof as the requirements of practice may dictate.

Hinged along a longitudinal edge of the box is a strip 4, provided with a hasp 8 adapted to engage and be secured to a staple or the like on the cover. To the 45 end edges of the box are hinged the strips 5, and 6, which are provided with the hooks 7, for engaging the cover when in applied position. In order to give a finish to the locked or closed box, a strip 3, is secured along an edge of the cover 2 opposite the edge of the box 50 having the strip 4.

When the cover has been placed upon the guides 9, the strips 4, 5, and 6, are swung over upon the cover and secured thereto by the hasp 8, and hooks 7, as will, it is thought be readily appreciated. The hooks 7 are 55 made operative by forcing the same by a suitable blow within the cover. This arrangement provides a means for securely holding the cover in place without the necessity of mutilating the box or receptacle by nails, screws and the like.

Having described my invention what I claim as new and desire to secure by Letters Patent is:—

In combination, a receptacle having one face open, guides arranged adjacent the free edges of the receptacle, a closure engaging the guides, strips hinged to the free 65 edges of the receptacle and adapted to rest upon the cover when in applied position on the guides, and fastening means carried by the strips to engage the cover to hold the strips in engagement with the cover.

In testimony whereof I have affixed my signature, in 70 presence of two subscribing witnesses.

PHILIPP METTMANN.
